UNITED STATES PATENT OFFICE.

HERBERT W. CHENEY, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

OIL-SWITCH.

1,240,314.

Specification of Letters Patent. Patented Sept. 18, 1917.

Original application filed March 27, 1909, Serial No. 486,171. Divided and this application filed September 16, 1910. Serial No. 582,301.

To all whom it may concern:

Be it known that I, HERBERT W. CHENEY, a citizen of the United States, residing at Milwaukee, in the county of Milwaukee and State of Wisconsin, have invented certain new and useful Improvements in Oil-Switches, of which the following is a full, clear, and exact specification.

My invention relates to oil switches, particularly to those of large capacity. This present application is a division of my pending application Serial No. 486,171, filed March 27, 1909.

One of the objects of the invention is the provision of a switch which can be safely employed in circuits of exceedingly high voltages and large amperages without any danger of the arcs causing injury to the operator or to any of the apparatus.

A further object is to provide for a switch of high capacity switch mechanism which is strong, durable and effective in operation, which is well insulated from the oil tank and other surrounding parts and which is so constructed that access may be readily had to all parts.

Other objects will appear hereinafter.

My invention consists in certain novel details of construction and combination and arrangements of parts which will be described in the specification and set forth in the appended claims.

I have in the present case shown my invention as applied to three pole switches such as are employed in three phase circuits, and have shown the contact mechanism of each pole inclosed within a separate oil compartment and receptacle. It is understood, however, that my invention is not limited in its scope to a switch of any particular number of poles and in many of its aspects is not limited to a switch having the mechanism of its poles arranged, constructed or inclosed as here shown.

For a better understanding of my invention, reference is had to the accompanying sheets of drawings, in which Figure 1 is a side elevation of a switch constructed in accordance with my invention, parts being broken away and other parts being in section;

Fig. 2 is a sectional view, taken through

one of the tanks and poles of the switch substantially on the line 2—2 of Fig. 1, the switch being here shown in its open position; 55

Fig. 3 is a sectional view, the section being taken between two of the poles and between the adjacent tanks or compartments, substantially along the line 3—3 of Fig. 1, the different parts of the operating mechanism being shown in the position which they occupy when the switch is closed;

Fig. 4 is an enlarged elevation of part of the stationary and movable contact members employed in each pole of the switch, 65 the contacts being separated or out of engagement;

Fig. 5 is a similar view showing the contacts in engagement and showing the relative positions of the parts when the switch 70 is closed;

Fig. 6 is a top plan view of one of the lower or stationary contact members;

Fig. 7 is a detail of the buffer employed in connection with the operating mechanism; and,

Fig. 8 is a similar view showing the manner in which the buffers are rocked when the switch closing movement starts.

Referring now to the figures of the drawing wherein I have shown the preferred embodiment of my invention, 10 represents a suitable switch-supporting frame which is provided with legs 11, and on which rest a number of oil tanks 12, in this case three 85 in number, said tanks being preferably formed of sheet metal and each being provided with a cover 12^a which is preferably divided along the longitudinal center or into two halves each of which is separately secured to the tank preferably by screws or bolts 12^b which pass through horizontal flanges 12^c on the cover and through horizontal flanges of angles 12^d secured to the tank and extending about the upper edge 95 of the same. Supported by the cover of each tank between the two parts of the same and near the ends thereof are insulators or insulating bushings 13 having vertical passageways which receive respectively conductors 14 which are surrounded by insulating sleeves 14^a, and each cover also supports between the parts or halves thereof and between the insulators 13, a pair of bushings 100

15 through which are adapted to reciprocate in a vertical direction, a pair of plungers 16, which are preferably made of wood and which form part of the operating mechanism to be explained later.

- 10 The different tanks 12 may be adjusted or held in fixed positions relative to the frame and to one another, and the passageways in the different bushings may be brought in absolute vertical alinement by several tank adjusting and holding devices including set screws 17 which extend through vertical flanges 10^a of the frame, or through short angles 10^b extending transversely across the frame between the tanks. 15 These set screws 17 engage the lower parts of the tanks on all four sides, and provide means whereby the tanks may be bodily shifted, or whereby the lower portions only 20 may be shifted while the upper parts are held stationary. The upper ends of the tanks are mutually braced and spaced apart by means of transverse threaded bolts or rods 18 passing through the vertical flanges 25 12^e extending downward from the covers, said bolts being provided at their threaded ends with nuts which permit the upper ends of the tanks to be adjusted relative to one another. The tanks are also held down to 30 the frame by pairs of tie rods 19 which are attached by means of bolts or screws 20 to opposite sides of the cover 12^a of at least the middle tank 12, and are adjustably connected at their lower ends by means of nuts 35 19^a to lugs 21 on the sides of the frame. By means of these various holding and adjusting devices the tanks can be held in proper position relative to one another and to the frame so as to permit the different parts of 40 the operating mechanism to work freely.
- In order that there may be between the contact mechanism or other live parts of the switch and the tank, a better insulation than that which is obtained by the oil alone, I 45 provide within each tank, and a short distance from the walls thereof, a casing or receptacle 26 which is made of insulating material such as wood and is provided with an open top, and between the bottom and 50 sides of this receptacle and the bottom and sides of the tank, I provide a number of separated or spaced layers 27 of insulating material such as fuller board, insulating supporting members 28 being provided at intervals between these different layers, so as to hold them predetermined distances apart. 55 Between the top of the inner casing 26 and the top of the tank is a separating collar 26^a of wood or other insulating material. This inner casing 26 and the insulating walls or 60 layers 27 are not oil tight, but the oil is permitted to enter between the different layers so that between the contacts and the metal walls of the tank there are alternate layers 65 of oil and of solid insulating material. This

arrangement provides a better insulation than the oil alone would provide, for the reason that when the oil is relied upon, the oil between a certain portion of the tank and a live part of the switch may be blown away or blown aside by the arc which will then remain established, causing immediate burning of the parts and destruction of the switch. Suitably supported by the bottom of the inner box or receptacle is a frame 70 75 of insulating material such as wood, and secured to this frame are three insulators 30, 31, and 32, which, as will be explained, support part of the contact mechanism. Between these insulators are arranged dividing partitions 33 and 34 preferably formed of separate spaced layers of insulating material, such as are provided along the bottom and sides of the tank.

The contact mechanism of each pole of the switch, which will now be explained, includes four yieldingly mounted main stationary contacts which are adapted to be bridged in a manner to be explained so as to provide a quadruple break or four point 90 break switch, the movable contacts being carried by vertically movable plungers and being given an upward movement away from the stationary contacts, when the switch is opened, so as to draw the arcs upwardly. Secured to the upper ends of the insulators 30 and 32 in each tank are metal caps 35 to the upper surfaces of which are secured, preferably by screws 37 (see Figs. 5 and 6) two similar cast metal contact holders or supporting castings 38 formed of good conducting material, such as brass. Each of these holders 38 is provided with a horizontal base 39 which engages the corresponding cap 35 and which extends laterally 105 beyond the corresponding insulator and is mechanically and electrically connected to one of the terminal rods 14, which, as stated before, extend down into the tank through the insulators 13, the lower ends of the terminal rods being screwed into threaded sockets in bosses 39^a of the holders. Each of these holders is provided also with an arm or bracket 40 which extends upwardly 110 from the base and is provided with a vertical 115 socket or guide 40^a (see Fig. 5) which receives one of the main contacts 41 having at its lower end a shoulder 41^a, which limits the upward movement of the contact and which is yieldingly supported and is pressed 120 upwardly by means of a rather heavy coil spring 43 located between the shoulder 41^a of the contact and the base of the holder. This contact 41 is connected to the base 125 of the corresponding holder by means of a flexible shunt or conductor 44 which is secured to the base by one of the screws 37 and to the lower end of the contact by means of a screw 45 and a washer 46, the latter being located intermediate the head of the 130

screw 45 and the end of the shunt. The arm or bracket 40 of the holder also supports a pivoted U-shaped arm or member 47, which is pivoted to the upper end of the bracket by means of a pin 48 passing through the bracket and through the free ends of the U-shaped member 47, and has at its forward end an auxiliary contact or arcing tip 49. The forward end of the pivoted member 47 and the contact 49 are yieldingly held upward so as to extend above the end of the contact 41, as shown clearly in the drawings, by means of a coil spring 50, one end of which engages a transverse pin 51 mounted in the bracket 40 a short distance above the base and the other end of which engages a pin 52 extending transversely between the ends of the pivoted member 47.

The insulator 31, which is located midway between the insulators 30 and 32, has secured to its upper end a cap 53 on the top of which is secured a casting or holder 54 which has two sets of main and auxiliary contact members such as are carried by each of the holders 38, the two sets being located near the opposite ends of the holder and being separated by a vertical barrier 55 which extends downward from the top of the wooden inner receptacle or casing 26 to the base of the casting 54. As will be apparent from Fig. 2 of the drawings, this contact holder or casting 54 has two main contacts 56, similar in all respects to the contacts 41 and yieldingly supported as the latter contacts are supported, and is provided also with two pivoted or swinging arms 57, which carry respectively auxiliary contacts or arcing tips 58 which are, as in the first instance, yieldingly held upward above the contacts 56, by springs. Thus it will be seen that each holder or contact supporting casting 38 and the corresponding main contact 41 constitute a single-break stationary contact member, while the contact supporting casting 54 and the two main contacts 56 carried thereby constitute a stationary bridging contact member having two main breaking points.

The movable contact members for each pole are carried by the plungers 16 which, as stated before, extend down through the bushings 15 which are mounted in the cover 12^a intermediate the insulators 13. Clamped to the lower ends of the plungers 16 are two U-shaped bridging conductors 60 and 61 each of which is secured to the corresponding plunger by a clamp 62. These conductors, which are formed of good conducting material, have downwardly projecting free end portions, and are so arranged that the free ends of one of the conductors are vertically above the contact 41 of one of the holders 38, and one of the contacts 56 of the middle holder, and the free ends of the other conductor are vertically above the contact 41 of

the other contact holder 38 and the other contact 56 of the middle holder. Secured to the lower ends of each of these conductors, are main movable contacts 63 and 64 which have threaded sockets and are screwed onto threaded lower ends of the conductors, as is shown clearly in Fig. 4. The lower faces of these contacts are adapted to engage the upper faces of the contacts 41 and 56 when the switch is closed. The bridging conductors 60 and 61 are also provided with auxiliary or arcing contacts 65 and 66 which are clamped between the upper ends of the main movable contacts 63 and 64 and lock nuts 67 and 68, the lower ends of the auxiliary contacts 65 and 66 extending downward below the lower ends of the main contacts 63 and 64 and being so located and so shaped that their lower ends will engage the upper ends of the auxiliary contacts carried by the stationary holders, when the switch is closed. When the plungers 16 are lowered, the auxiliary contacts 65 and 66 engage the auxiliary contacts 49 and 58, pressing the latter downward to the position shown in Fig. 5, and the contacts 63 and 64 engage the contacts 41 and 56 respectively with sufficient force to press the latter contacts downward a short distance against the tension of the springs 43, so that the latter will cause the main contacts to be held together under a considerable degree of pressure. The contacts 41 and 56 have, as shown clearly in Figs. 5 and 6, a limited play in the sockets 40^a which receive the contacts so that the latter may adjust themselves in the socket to accommodate any unevenness or irregularity of the adjacent engaging contact faces.

The upper ends of the two plungers 16 of each pole of the switch are connected together by a cross-bar 69, which, together with the plungers 16, constitute the yoke. All the cross-bars are connected together by a bar or beam 70 which extends horizontally above all the tanks. Secured to the upper beam 70 are two vertically movable operating plungers or rods 71, which extend downward between the tanks and are supported and guided for vertical movement by two frames 73, supported on the frame 10 between the tanks, each frame being somewhat triangular in shape and being provided at the top with a boss or hub 74 and at the bottom with a boss or hub 75 having vertical bores or passageways through which the corresponding plunger or rod 71 is adapted to slide. The switch is adapted to be closed by an electro-magnetic motive device, preferably in the form of a solenoid, and is adapted to be opened with an exceedingly quick movement by means of weights and springs which act upon the plungers 71. For this purpose the plungers 71 are provided below the upper bosses 74 with collars 76, which

are secured to the rods by transverse pins 77, and between the collars 76 and the lower bosses of the frames and surrounding the plungers 71 are rather heavy coil springs 78 which will be compressed when the plungers

5 are drawn downward.

Secured to the lower side of the frame 10 and below the middle tank 12 are two cast metal plates 79 which form a supporting 10 frame for part of the switch operating mechanism. These plates 79 are provided with bosses or bearings 80 in which is supported a shaft 81 which extends outwardly beyond the bearings of each of the plates 79 15 as shown clearly in Fig. 1. Secured or fixed to the outer ends of this shaft 81 are two levers 82, to the outwardly projecting ends of which are secured weights 83, and the forwardly or inwardly projecting ends 20 of which are operatively connected to the collars 76 which are secured to the movable plungers 71. In this case the inner end of each lever 82 is connected to the corresponding collar 76 by a pair of links or 25 straps 86.

Secured to the lower sides of the plates 79 is a casing 88 for a switch-closing solenoid 89 and for a tripping solenoid 90. These solenoids 89 and 90 may be controlled in any suitable manner, one desirable way of doing so being that set forth in my aforesaid co-pending application of which this application is a division. The closing solenoid includes a coil 91 and a core 92 which extends upwardly through the cover 93 of the casing, and this core is connected by a link 94 to one arm 95 of a bell-crank lever 96 which is secured to the shaft 81 between the two plates 79, 30 so that when the core is drawn into the coil 91, the bell-crank 96, shaft 81 and weight carrying levers 82 will be rocked, swinging the inner ends of the levers 82 downward and the outer ends of the levers and the 35 weights carried thereby upward. The links 86 and consequently the plungers 71 will therefore be drawn downward, compressing the coil springs 78 which surround the plungers 71, and closing the switch. In 40 order that the switch may be held in the closed position, I have provided a toggle consisting of two arms 97 and 98, pivotally connected together by a pin or stud 99, and the former being connected by means 45 of a pin or stud 100 to an arm 101 of the bell-crank lever 96 and the latter being pivotally supported on the two plates 79 by means of a transverse pin or shaft 102 extending between the plates. The inner end 50 of arm 98 of the toggle extends beyond the connecting pin 99 and is provided with a notched or hooked portion 103. Thus it will be seen that when the switch is closed by the solenoid 89, the movement of the 55 bell-crank 96 will cause the arms 97 and 98

to be merely straightened and will cause the connecting pin 99 to be raised to a point just below a straight line between the pins or centers of movement 100 and 102. Any suitable stop device may be employed for

70

limiting the movement of the toggle arms toward a straight line. To hold the toggle in this position, I have provided a holding and tripping device consisting of a latch 104 pivoted between the two plates 79 and

75

having at its upper end a roller 105 which is adapted to be engaged by the notched portion 103 of the arm 98 of the toggle and having its lower end directly above a hammer 106 which projects above the cover 80 85 93 of the casing and is adapted to be struck and shifted upwardly by the core 107 of the tripping solenoid 90. The latch 104 is normally held in the position shown in

Fig. 2 by means of a small coil spring 108, 85 and when the switch is closed by the solenoid 89 and the arms of the toggle are brought nearly in a line, the notched or hooked portion 103 of the toggle arm 98 will be swung above the roller 105 at the 90

end of the latch 104 and will be retained in that position. When, the coil 109 of the tripping solenoid 90 is energized, the hammer 106 will be given a blow by the core 107, the latch will be rocked and the upper 95

end will be swung inward out of engagement with the notched or hooked portion of the toggle arm 98, with the result that the switch will be immediately opened with an exceedingly quick movement by the force 100 of gravity acting on the weights and by the action of the coil springs 78. The arm 98 of the toggle is provided with an extension 110 having a socket 111 in which is adapted to be inserted the end of a suitable 105 bar or lever by means of which the switch may be closed by hand.

Suitable buffers are provided for cushioning the movement of the switch mechanism when the switch is opened, and this buffer mechanism is as follows: At the lower ends of the rods 71 are provided nuts 112 having conical or inwardly tapered surfaces, and arranged on diametrically opposite sides of each rod 71 are two hollow 115 buffer blocks 113 having tapered inner ends adapted to be engaged by the tapered portion of the corresponding nut. These buffer blocks are supported on the lower sides of the triangular shaped frames 73 between 120 pairs of downwardly extending lugs or ears 114 and upon cross pins 115 extending between the ears. The blocks have elongated slots 116 which extend in the direction of the lengths of the blocks, and through 125 which the pins 115 loosely pass, so that the blocks may turn or rotate on the pins and also may move longitudinally. Secured on the interior of each of the hollow blocks 113 by means of the cross pin 115 is 130

a pin or plug 117 and intermediate the inner end of the block, which end is closed, and the end of the corresponding pin or plug 117 is a yieldable or elastic cushioning medium 118 preferably a block of rubber. The outer ends of the blocks are heavier than the inner ends and tend to hold the blocks in a horizontal position with the inner ends abutting against stop lugs 119 above the blocks. The inner ends of the blocks are therefore prevented by these stop lugs from rocking or turning upwardly beyond the horizontal position of the blocks but may swing downward. The result of this construction is that when the rods 71 are near the upward limit of their travel during the opening movement of the switch, the wedge-shaped nuts 112 on the lower ends of the plungers will engage the inner ends of the buffer blocks 113, causing the same to be spread apart or moved outwardly in a horizontal direction and causing the rubber blocks 118 to be compressed between the pins or plugs 117 and the closed ends of the buffer blocks. When the rods 71 are moved downward or when the switch is closed, the wedge-shaped nuts on the rods 71 will pass from between the buffer blocks, the latter swinging downward as shown in Fig. 8, to permit the rods and wedge-shaped nuts to readily move downward.

It will be seen that on account of the construction of the switch itself, the particular arrangement of the coöperating contact members and the manner of insulating the same, the quick movements with which the contacts are separated, and the particular construction and arrangement of the operating mechanism, there is provided a switch in which dangerous and destructive arcing at the contacts is reduced to a minimum.

It is to be noted also that access can be readily had to all parts of the switch mechanism even though part of the mechanism is supported on the lower part of the tank. The movable switch mechanism can be removed as a unit from each tank after the beam 70 and the cover are removed, and in case it is necessary to inspect or repair the stationary switch mechanism, the supporting frame 29 and all the apparatus carried thereby, including the switch supporting insulators and the contact mechanism supported by the insulators, can be simultaneously lifted from the tank by grasping the terminal rods and drawing the same and all the parts connected thereto, upward out of the tank, the insulating barriers 33 and 34, being of course, first removed from the tank.

I do not desire to be confined to the exact details, but aim to cover all modifications which do not involve a departure from the spirit and scope of my invention as set forth in the appended claims.

What I claim as new is:

1. In an oil switch, an oil tank, a casing of insulating material within and spaced from said tank, switch mechanism within said casing, and a plurality of spaced insulating elements between said tank and casing, said insulating elements having portions lying across said tank between the bottom thereof and said casing. 70

2. In combination, a plurality of switches each contained in a separate casing, actuating mechanism for said switches, a support for said casings, and means for adjusting said casings relatively to each other and to said actuating mechanism comprising adjusting means between the lower part of each casing and said support and adjustable spacing means between the upper parts of the individual casings. 80

3. In combination, a plurality of switches, a casing for each switch, a support for said casings, switch operating means supported in fixed relation to said support, and means for adjusting said casings relatively to each other and to said support to properly align the switch parts, said adjusting means including adjustable spacing devices between the individual casings and independent of said support. 90

4. In an oil switch, an oil tank, an insulating support mounted in said tank, a contact holder of conductive material carried by said support, said holder having a base and a portion supported thereby and provided with an extension substantially parallel to the adjacent side of said base and spaced therefrom, said extension being provided with a guiding recess, a contact in said recess, a spring intermediate the base of said holder and said contact and pressing the latter away from said base, said spring being insertible into operative position from the side of said extension adjacent said base. 100

5. In an oil switch, an oil tank, a plurality of insulating supports mounted in said tank, contact holders mounted on said supports, each holder having a vertical socket, a main contact yieldingly supported therein, and a pivoted arm embracing said main contact and carrying an auxiliary contact, and a vertically movable bridging contact member having downwardly projecting ends provided with main contacts adapted to engage the upper ends of the main contacts carried by the holders, and auxiliary contacts adapted to engage the auxiliary contacts carried by the holders. 110

6. In an oil switch, an oil tank, a plurality of separate insulators mounted in said tank, a contact holder mounted upon the upper end of each insulator, two of said holders each having a terminal rod connection and a contact on the same side of the supporting insulator, each contact being yieldingly sup- 125

- ported so as to be capable of vertical movement, another holder intermediate said two holders having a pair of contacts yieldingly supported, and a pair of plungers extending downward into the tank and having bridging conductors provided at their ends with contacts adapted to engage the contacts carried by said holders. 70
7. In an oil switch, an oil tank, a frame mounted in the lower part of said tank, a series of spaced insulators extending upward from said frame and secured thereto, contact holders mounted upon the upper ends of said insulators and being arranged in a row, the holders on the two outer insulators having terminal conductors connected thereto and each having a single main contact yieldingly supported so as to be capable of a slight vertical movement and having a yieldingly supported auxiliary contact, and a third holder on an insulator intermediate the other two insulators, said third holder having two main contacts and two auxiliary contacts all yieldingly supported, a pair of plungers extending downwardly into the tank, bridging conductors, carried by said plunger and having at their lower ends main and auxiliary contacts adapted to engage the main and auxiliary contacts carried by said holders. 80
8. In an oil switch, an oil tank, an insulating frame mounted in the lower portion of said tank, said frame carrying a plurality of separate insulators, contact holders mounted upon the upper ends of said insulators, terminal conductors extending downward into the tank and connected to the holders on the two outer insulators, each of said last named holders having a main contact yieldingly supported so as to be capable of a slight vertical movement, and a pivoted member provided with an auxiliary contact, a third holder intermediate the outer holders, said third holder having a pair of main contacts yieldingly supported so as to be capable of slight vertical movements, and having a pair of pivoted members provided with auxiliary contacts, vertically movable plungers extending downward into the tank, bridging contact members carried by said plungers and having at their ends main and auxiliary contacts adapted to engage the main and auxiliary contacts of said holders. 90
9. In an oil switch, an oil tank having a cover divided longitudinally into two separable parts, a plurality of insulating supports mounted in said tank, contact holders provided with contacts secured to said supports, a plurality of insulating bushings carried by said cover intermediate the parts thereof, terminal conductors extending downward into the tank through two of said bushings and connected to two of the contact holders, a plurality of plungers extend- 100
- ing downward into the tank through two other of said bushings and having bridging contact conductors provided at their lower ends with contacts adapted to engage the contacts carried by the holders associated with said terminal conductors and other of said first mentioned contacts. 110
10. In combination, in a switch, contact mechanism, switch operating mechanism comprising a longitudinally movable member, cushioning devices for limiting the movement of said member comprising hollow members which are mounted adjacent to and are movable laterally by said longitudinally movable member, and a cushioning medium within each of said hollow members. 120
11. In combination, in a switch, contact mechanism, switch operating mechanism comprising a longitudinally movable rod, cushioning devices for said switch mechanism comprising a pair of members mounted on opposite sides of said rod, said rod having means adapted to move said members outwardly, and an elastic cushioning medium adapted to be compressed by each of 90 said outwardly movable members. 130
12. In combination, in a switch, contact mechanism, switch operating mechanism comprising a longitudinally movable rod, means for cushioning the movement of said operating mechanism comprising members slidably mounted on opposite sides of said rod and adapted to be moved outwardly by the same, and elastic devices compressed by the outward movement of said members. 140
13. In combination, in a switch, contact mechanism, switch operating mechanism comprising a vertically movable rod, a tapered member on said rod, means for cushioning the movement of said mechanism 105 comprising a pair of buffers on opposite sides of the rod in position to be engaged and to be moved outwardly by said tapered member. 150
14. In combination, in a switch, contact mechanism, switch operating mechanism comprising a longitudinally movable rod, and means for cushioning the movement of said operating mechanism comprising a tapered member on said rod, a pair of pivoted 110 and longitudinally movable blocks on opposite sides of said rod in position to be engaged and spread apart by said tapered member when the rod is moved in one direction, a relatively stationary member and a 120 cushioning medium within each block. 160
15. In combination, a frame provided with a supporting platform having one or more angular projections extending therefrom, a plurality of oil receptacles supported side 125 by side on said frame, a switch mechanism in each receptacle, and means for spacing said receptacles and holding the same in position on the frame comprising adjustable screws extending through said projection or 130

- projections on the frame and engaging the sides of the receptacles.
16. In combination, in a multipole switch, a frame, a plurality of tanks supported on said frame, and means for definitely positioning said tanks relative to one another comprising spacing bolts extending between the upper portions of adjacent tanks and screws engaging opposite sides of the lower portions of the tanks.
17. In combination, a multipole switch, a frame, a plurality of tanks supported side by side on said frame, means for holding said tanks in definite positions relative to one another and to the frame comprising set screws engaging opposite sides of the lower portions of the tanks, adjustable rods or bolts extending between the upper portions of adjacent tanks, and adjustable tie rods connecting the upper portions of the tanks to the frame.
18. In combination, in a multipole oil switch, a horizontal frame, a plurality of tanks side by side on said frame, adjustable means between the tanks for holding the same in relatively fixed positions, and adjustable tie rods extending between the upper ends of the tanks and the sides of the frame.
19. In a switch, a contact holder of conductive material and comprising a body portion and an extension therefrom, a main contact movable in said recessed portion, an auxiliary contact pivoted to said extension, and yielding means between said main contact and the body portion of said contact holder for urging said contact away from said holder.
20. In a switch, the combination of a contact support of conductive material and comprising a body portion and a portion supported thereby and spaced therefrom, said latter portion being provided with a guiding recess, a contact in said recess, said contact being insertible in said recess from the side adjacent said body portion, and means for urging said contact away from said body portion.

Milwaukee, Wisconsin, September 3, 1910.

In testimony whereof I affix my signature, in the presence of two witnesses.

HERBERT W. CHENEY.

CLARA E. BENSEL.

Correction in Letters Patent No. 1,240,314.

It is hereby certified that in Letters Patent No. 1,240,314, granted September 18, 1917, upon the application of Herbert W. Cheney, of Milwaukee, Wisconsin, for an improvement in "Oil-Switches," an error appears in the printed specification requiring correction as follows: Page 7, line 32, claim 19, after the word "therefrom" and before the comma insert the clause *provided with a recessed portion approximately parallel to the adjacent face of said body portion;* and that the said Letters Patent should be read with this correction therein that the same may conform to the record of the case in the Patent Office.

Signed and sealed this 29th day of January, A. D., 1918.

[SEAL.]

Cl. 175—283.

R. F. WHITEHEAD,
Acting Commissioner of Patents.
